(57) CLAIM

The ornamental design for a first aid product supply container, as shown and described.

DESCRIPTION

FIG. 1 is a front, right, perspective view showing my design of a first aid product supply container;

FIG. 2 is a back elevation view thereof;

FIG. 3 is a top plan view thereof;

FIG. 4 is a bottom plan view thereof;

FIG. 5 is a left side elevation view thereof;

FIG. 6 is a front elevation view thereof; and,

FIG. 7 is a right side elevation view thereof.

The broken lines showing tabs extending from the container are for illustrative purposes only and form no part of the claimed design.
